US00D945159S

(12) United States Design Patent (10) Patent No.: US D945,159 S
Cooper et al. (45) Date of Patent:  Mar. 8, 2022

(54) CONTAINER

(71) Applicant: WVC Holdings, Inc., Denver, CO (US)

(72) Inventors: Jeremy Cooper, Denver, CO (US);
Jeremiah Buck, Denver, CO (US);
Timothy Hanley, Denver, CO (US);
Zachariah Johnson, Denver, CO (US)

(73) Assignee: WVC Holdings, Inc., Denver, CO (US)

() Term: 15 Years

(21) Appl. No.: 29/749,765

(22) Filed: Sep. 9, 2020

Related U.S. Application Data

(63) Continuation of application No. 29/670,449, filed on Nov. 15, 2018, now Pat. No. Des. 896,519.
